W. R. SILVERTHORNE

HARROW LIFTER

Filed Jan. 9, 1925.

UNITED STATES PATENT OFFICE.

WILLIAM RALPH SILVERTHORNE, OF SHELL BROOK, SASKATCHEWAN, CANADA.

HARROW LIFTER.

Application filed January 9, 1925. Serial No. 1,500.

To all whom it may concern:

Be it known that I, WILLIAM RALPH SILVERTHORNE, a subject of the King of Great Britain, and a resident of the village 5 of Shell Brook, in the Province of Saskatchewan, Canada, have invented certain new and useful Improvements in Harrow Lifters, of which the following is the specification.

10 My invention relates to improvements in harrow lifters, and the object of the invention is to devise a simple and convenient means whereby any one of the harrow sections may be independently lifted by the 15 operator when seated on a follower carriage travelling behind the harrow sections, and it consists essentially of the arrangement and construction of parts hereinafter more particularly explained.

20 Fig. 1 is a perspective view showing my harrow lifter applied to a harrow.

Fig. 2 is an enlarged sectional detail showing the means whereby the carrier wheels of the follower carriage are mounted upon 25 the carriage.

In the drawings like characters indicate corresponding parts in each figure.

1 and 2 indicate carrier wheels provided with stud axles 3, each axle being provided 30 with an upwardly vertical extension 4.

The stud axles 3 are connected together by angle bars 5 and 6 which are connected together by plates 7.

35 8 are standard brackets secured at their foot end as indicated at 9, to the angle bars 5 and 6, serving also to connect such angle bars together.

The upper end of each standard bracket 40 8 is outturned as indicated at 10, to form an upper bearing support for the vertical portion 4 of the stud axle 3, the lower end of such vertical portion being permanently held in the cross plates 7, as clearly indicated in fig. 2.

45 The lower portion of the stud axle is provided with an enlargement 11 bearing against the lower face of the plates 7, a nut 12 being threaded intermediately of the vertical portion 4 against the out-turned portion 10 of the bracket 8.

By this means, the axles are held perman-

ently in position and from vertical movement.

13 are arms which are secured to the upper ends of the portions 4 of the stud axles 55 3, such arms extending forwardly and connected together in proximity to their forward ends by a cross bar 14, such cross bar carrying a series of loops or eyelets 15, for a purpose which will hereinafter appear. 60

The cross bar 14 is pivotally connected to each arm 13 by a pivot bolt 16.

17 is a transverse bar on which are mounted pulley blocks 18, 19, 20, 21, 22, 23, 23^x, 24 and 25. 65

26 is a draft arm which is preferably V shaped in form, the arms of the V being provided with saddle portions 27 extending over the transverse bar 17, and secured thereto, the extreme ends of the arms extending downwardly, as indicated at 28, to the angle bars 5 and 6 extending transversely of such bars, as indicated at 29, (Fig. 2), being secured thereto by bolts 30 further securing the bars 5 and 6 together. 75

31 are a series of harrow sections connected to the harrow beam 32 to which the harrows are connected by chains 33 in the usual manner.

34 is a block secured to the beam 32 intermediately of its length. 80

35 is a goose neck formed at the apex of the V shaped harrow lifting arm 26, such goose neck depending therefrom and being provided with a foot 36 resting upon the block 34 and connected thereto by a king bolt 37. 85

38 and 39 are tie rods having hooks 40 at their upper ends extending through orifices 41 of the arms 13, and at their opposite ends being provided with hooks 42 extending through orifices 43 formed in brackets 44 which are pivotally connected, as indicated at 45, to the harrow beam 32. 90

By this means a flexible connection is 95 formed between the ends of the arms 13 and the harrow beam 32, permitting the arms 13 to have a limited swinging movement to permit the carrier wheels 1 turning in the desired direction to follow the harrow. 100

It will of course be understood that as the harrow is drawn over the ground, in

turning, the harrow beam swings horizontally and a pull is exerted either on one tie rod or the other, which thereby swings the arms 13 connected together by the cross bar 14 in the desired direction to turn the wheels 1 and 2 in unison.

46, 47, 48, 49 and 50 are cords or cables, each cord being connected to a harrow section 31. The cord 46 passes upward over

10 the pulley block 18, and then passes longitudinally of the bar 17 around the pulley block 20 and through an eye 15, the end of the cord depending and formed into a loop 51.

15 Similarly, the cord 47 is connected to the next harrow section in succession and passes upward over the pulley block 19, and then transversely of the machine between the bar 17 and from thence through the next eye 15 in succession, its depending end being

20 also formed into a loop, as indicated. The cord 48 passes upward from the third harrow section in succession, over the pulley block 22 and through the third eye 15, its depending end also being in loop form.

25 The cords 49 and 50 pass upward from the 4th and 5th harrow sections and over the pulleys 24 and 25, passing transversely of the machine round the pulleys 23 and 23^x, through the 4th and 5th eyes 15, the ends being also formed with loops.

30 The loops 51 form hand-grips by which the operator seated in the seat 52, by pulling upon any one of the cords 46, 47, 48, 49 or 50 can independently raise any one of the harrow sections 31 so as to free it from weeds or any other matter clogging thereon.

35 From this description it will be seen that I have devised a very simple form of harrow lifter which will be very effective, easily operable, and which will follow the harrow in any desired direction.

40 What I claim as my invention is:

1. The combination with a harrow beam, 45 and the harrow sections connected thereto, of a harrow lifter comprising a follower carriage provided with stud axles, a pair of carrier wheels mounted on the stud axles, a transverse member connecting the axles together, a vertical extension to each axle, means for turnably mounting each vertical extension on the transverse member, means connecting the vertical extensions to the harrow beam whereby the horizontal swing of the harrow beam is transferred to the vertical members to turn them in a corresponding direction to guide the carrier wheels to track with the harrow.

50 2. The combination with a harrow beam, and the harrow sections connected thereto, of a harrow lifter follower carriage comprising a pair of carrier wheels provided with stud axles, a transverse member connecting the axles together, a vertical extension to each axle, means for turnably mount-

55 ing each vertical extension on the cross member, means connecting the vertical extensions to the harrow beam whereby the horizontal swing of the harrow beam is transferred to the vertical members to turn them in a corresponding direction to guide the carrier wheels to track with the harrow, and means whereby the carriage wheels are turned in unison.

60 3. The combination with a harrow beam, and the harrow sections connected thereto, of a harrow lifter follower carriage comprising a pair of carrier wheels provided with stud axles, a transverse member connecting the axles together, a vertical extension to each axle, means for turnably mounting each vertical extension on the cross member, means connecting the vertical extensions to the harrow beam, an arm extending forwardly from each vertical extension, 80 a cross rod pivotally connecting the arms together, tie rods extending from each arm and crossed intermediately of their length and pivotally connected at their opposite ends to the harrow beam, and means connected to each harrow section whereby each harrow section may be independently lifted by the operator from a point behind the follower carriage.

65 4. The combination with a harrow beam, and the harrow sections connected thereto, of a harrow lifter follower carriage comprising a pair of carrier wheels provided with stud axles, a transverse member connecting the axles together, a vertical extension to each axle, means for turnably mounting each vertical extension on the cross member, means connecting the vertical extensions to the harrow beam, an arm extending forwardly from each vertical extension, 100 a cross rod pivotally connecting the arms together, a series of parallel pull cords guided on cross rod, tie rods extending from each arm and crossed intermediately of their length and pivotally connected at their opposite ends to the harrow beam, a transverse bar member carried by the harrow beam arm, and pulley blocks mounted thereon around which the aforesaid pull cords extend individually from each harrow section.

70 5. The combination with a harrow beam and the harrow sections connected thereto, of a harrow lifter follower carriage comprising a pair of carrier wheels provided with stud axles, a transverse member connecting the axles together, a vertical extension to each axle, means for turnably mounting each vertical extension on the cross member, means connecting the vertical extensions to the harrow beam, an arm extending forwardly from each vertical extension, 110 a cross rod pivotally connecting the arms together, tie rods extending from each arm and crossed intermediately of their length and pivotally connected at their opposite ends to the harrow beam, a transverse bar member carried by the harrow beam arm, and pulley blocks mounted thereon around which the aforesaid pull cords extend individually from each harrow section.

75 6. The combination with a harrow beam and the harrow sections connected thereto, of a harrow lifter follower carriage comprising a pair of carrier wheels provided with stud axles, a transverse member connecting the axles together, a vertical extension to each axle, means for turnably mount-

length and pivotally connected at their opposite ends to the harrow beam, a transverse bar member carried by the draft arm, pulley blocks mounted thereon, a cord extending from each harrow section and guided by the pulley blocks and extending in transverse series over the bar connecting the arms extending from the vertical extensions of the axle arms, eyes carried by such transverse bar through which the cords individually pass, and a loop formed by the depending portion of each cord to form a hand-grip whereby each cord may be independently pulled by the operator. ¹⁰

WILLIAM RALPH SILVERTHORNE.
